UNITED STATES PATENT OFFICE.

FREDERICK JAMES BIGGS, OF LONDON, ENGLAND.

LATCH AND LOCK COMBINED.

SPECIFICATION forming part of Letters Patent No. 311,637, dated February 3, 1885.

Application filed April 9, 1884. (No model.) Patented in England October 2, 1883, No. 4,675.

To all whom it may concern:

Be it known that I, FREDERICK JAMES BIGGS, of London, England, have invented certain new and useful Improvements in Latch-locks, of which the following is a specification.

This invention relates to that class of latch-locks wherein, by means of a key, the latch may be shot beyond its normal protrusion in order to lock the door, the bolt being at the same time disconnected from the knob.

The object of my invention is to improve the construction of such latch-locks in order to correct certain defects to which, as heretofore constructed, they have been subject.

15 The accompanying drawings show my improved latch-lock in its preferred form. Figure 1 is a side elevation of the lock, with the parts in the normal or unlocked position, one side of the lock-case being removed and the front plate being in section. Fig. 2 is a similar view, but showing the latch-bolt shot forward and locked, and also showing the knob or handle turned as in the act of opening the latch. Fig. 3 is a transverse section on line 20 3-3 in Fig. 1. Fig. 4 is a horizontal mid-section of Fig. 2. Fig. 5 is a front view of the two parts of the bolt, and Fig. 6 is a plan of the same.

Let *a* designate the lock-case; *b*, the front plate; *c*, the spindle of the knob or handle, and *d* a sleeve or boss, having a square hole to receive the spindle. The latch-bolt is in two parts, *g* and *h*, as shown best in Figs. 5 and 6. The part *h* is at the front and bears or is connected to the beveled latch *i*. The part *g* at the rear is formed with beveled faces *f*, which are acted upon by horns or arms *e* on the boss *d*, which is turned by the spindle *c*. Thus the turning of the spindle to either side presses 30 back the part *g* of the bolt against the tension of a spring, *o*, which is mounted on a pin, *p*, and reacts against a fixed post, *q*, Fig. 4. The parts *g* and *h* of the bolt are connected together only through a tumbler, *m*, which is 35 pivoted at *n* to the part *h*, and has a notch, *l*, which engages a tooth, *k*, on the part *g* of the bolt, as shown in Fig. 1. This engagement is only when the latch is unlocked. At such time the two parts of the bolt are thus connected together, and the turning of the knob or handle moves back the entire bolt and

draws in the beveled latch *i*, the spring *o* being thus compressed ready to return the parts to their normal position when the handle is released.

55 In order to lock the latch, a key is inserted at the hole *r* and turned. It first lifts the tumbler *m* clear of the tooth *k*, and then moves this tumbler forward, together with the latch, into the position shown in Figs. 2 and 4. The tumbler being then clear of the tooth *k*, it follows that when the handle is turned it moves only the rear portion, *g*, of the bolt, as shown in Fig. 2, and the front portion, *h*, and latch *i* are not moved. When the latch is again 65 unlocked by turning the key, the tumbler is first lifted and then moved back with the part *h* of the bolt, and in falling its notch *l* again engages the tooth *k*.

In latch-locks of this character prior to my 70 invention the tooth *k* and the end of the tumbler have both been made with abrupt faces, the result being that, if the bolt be unlocked while the handle is turned, the release of the handle causes the part *g* of the bolt to spring 75 forward, and its tooth *k* strikes dead against the end of the tumbler, and, if the spring be strong enough, shoots the bolt again, or at the least leaves the latch blocked and inoperative. In my improved construction of latch both 80 the reshooting of the bolt and the blocking of the latch under such circumstances are prevented, and the springing forward of the rear part of the bolt upon the release of the handle is made to couple the two parts of the bolt together again and leave the latch operative.

85 It will be seen by referring to Figs. 1 and 2 that the tumbler *m* is formed with a tooth, *u*, having its rear side beveled, and that the tooth *k* is also beveled on its upper front side. 90 It is not necessary that both these teeth be thus beveled, as it will suffice if only one be beveled. If, while the handle is turned, as shown in Fig. 2, the latch should be withdrawn by turning the key, then on the release 95 of the handle the part *g* of the bolt will spring forward, and in doing so its tooth *k* will encounter the tooth *u* on the tumbler, and by reason of their beveled faces (or a beveled face on one of them) will lift the tumbler and pass 100 under it into the notch *l*, whereupon the tumbler will drop back, leaving the latch in oper-

ative condition and unlocked. Thus no possible blocking or disarrangement of my improved latch-lock can occur from any ordinary cause.

5 I also provide means for retaining the bolt *h* and latch *i* in either position, locked or unlocked, thus preventing their displacement until they are intentionally displaced by the key or handle. This means consists of a tooth, 10 *s*, formed on the under side of the tumbler, and a fixed tooth, *t*, formed on the case. As the tumbler is lifted by the key its tooth *s* clears the tooth *t*, and as the tumbler falls again its tooth comes upon the opposite side of the latch. 15 When the latch is shot or locked, the teeth *s* *t* stand in such positions as to prevent its retraction, and when it is retracted, as in Fig. 1, they stand in such position as to prevent its being shot farther out, but do not prevent its being drawn farther in by turning the handle.

The general construction of my improved latch-lock is such as to secure simplicity of parts and great compactness, thus adapting 20 the lock to a slender cylindrical case.

I am aware of the constructions of locks shown in English Patent No. 87 of 1871, upon certain of which my present invention is an improvement.

25 What I claim as new, and desire to secure by Letters Patent, is—

1. The combination, to form a latch-lock, of a latch-bolt divided into two parts, the beveled latch borne by one of said parts, the knob-spindle connected to and actuating the other 35 of said parts, a tumbler pivoted to one part of the bolt, a tooth or projection on the other part thereof, adapted to be engaged by said tumbler or disengaged therefrom, and a beveled face on said tooth or tumbler, or both, 40 substantially as set forth, whereby when the tooth is moved against the tumbler it will displace the latter and engage with it.

2. The combination, to form a latch-lock, of a latch-bolt divided into two parts, the knob-spindle connected to and actuating the rear 45 part, a tumbler pivoted to the front part, and adapted to engage the rear part, a tooth, *s*, on said tumbler, and a fixed tooth, *t*, on the case of the lock, substantially as set forth, whereby 50 the interlocking of said teeth *s* *t* prevents the retraction of the latch when it is shot and the shooting of the same when it is retracted.

In witness whereof I have hereunto signed my name in the presence of two subscribing 55 witnesses.

FREDERICK JAMES BIGGS.
